US0D1002875S

(12) **United States Design Patent** (10) **Patent No.:** **US D1,002,875 S**
(45) **Date of Patent:** **** Oct. 24, 2023**

(54) **BUILDING MATERIAL**

(71) Applicant: **TECHNOTRON—METAL s.r.o.**,
Chrudim (CZ)

(72) Inventors: **Tomáš Mischinger**, Markvartovice
(CZ); **Jiří Polášek**, Frýdek Místek (CZ)

(73) Assignee: **TECHNOTRON—METAL s.r.o.**,
Chrudim (CZ)

(**) Term: **15 Years**

(21) Appl. No.: **29/772,018**

(22) Filed: **Feb. 26, 2021**

(30) **Foreign Application Priority Data**

Oct. 22, 2020 (EM) 008212302-0003

(57) **CLAIM**

The ornamental design for a building material, as shown and described.

DESCRIPTION

FIG. 1 is a front and right-side perspective view of a building material;

FIG. 2 is another front and right-side perspective view of the building material of FIG. 1;

FIG. 3 is a back perspective view of the building material of FIG. 1;

FIG. 4 is an enlarged front perspective view of a portion of the building material of FIG. 1; and,

FIG. 5 is a front perspective view of the building material of FIG. 1.

The broken lines depict the limits of the enlarged views and form no part of the claimed design.

1 Claim, 5 Drawing Sheets
